PRINTING APPARATUS

John Q. Sherman, Dayton, Ohio

Application December 14, 1936, Serial No. 115,804

39 Claims. (Cl. 101—228)

This invention relates to printing apparatus, and more particularly to automatic mechanism for printing form letters, circulars and the like, employing therefor continuous web or series connected stationery which, after the printing operation, is automatically sub-divided into successive sheets.

The present apparatus is designed for use in
mercantile and industrial establishments for
10 rapidly multigraphing letters, bills and circulars
for which continuous web printed stationary in
roll or packet form shall have been previously
prepared, although it may be employed for gen-
15 eral type printing of hand bills circulars and
forms.

The web of stationary is preferably pre-printed with a succession of letterheads at spaced intervals, forms or other indicia, in predetermined relation with which successive letter print impressions are to be effected.

20 A continuously rotating drum carries the printing type which may be either directly inked or operate through an overlying inked ribbon to effect an impression in a manner similar to the well known multigraphing machines. While the 25 printing cylinder, of which only a small portion of the periphery may be occupied by printing type, rotates continuously, the paper feeding mechanism is operated intermittently through 30 step by step movement, the length of the steps being variable in accordance with the size of the desired printed sheet. Paper feed devices of positive character are employed, which preferably, though not necessarily, are of the pin 35 wheel type, the pins of which progressively engage in spaced marginal holes in the paper web. Subsequently to the printing operation the punched margins of the printed web are trimmed off and the web is transversely cut intermediate 40 succeeding impressions into printed sheets.

40 The object of the invention is to simplify the construction as well as the means and mode of operation of continuous web printing apparatus whereby it will not only be cheapened in construction, but will be more efficient in operation, automatic in action, rapid, accurate and uniform in production of printed material, and unlikely to get out of repair.

50 A further object of the invention is to provide an improved form of differential actuating means for the printing cylinder and the paper web feeding apparatus whereby the paper is advanced in unison with the rotation of the printing cylinder during the impression making interval whether such be long or short and be given further ad-

vance movement either in advance or subsequent to the impression contact of the cylinder, the extent of such advance movement being entirely independently of the movement of the cylinder to afford a sheet length of predetermined extent. 5

A further object of the invention is to provide in combination with such printing apparatus, a positive feed mechanism for the paper web, and to provide slitting means for removing marginal portions of the web employed for feeding purposes subsequently to the printing operation. 10

A further object of the invention is to provide a compact, inexpensive apparatus adapted for use in commercial and mercantile establishments and which may be operated by unskilled persons. 15

With the above primary and other incidental objects in view as will more fully appear in the specification, the invention consists of the features of construction, the parts and combinations thereof, and the mode of operation, or their equivalents, as hereinafter described and set forth in the claims.

Referring to the accompanying drawings wherein are shown the preferred, but obviously not the only form of embodiment of the invention, Fig. 1 is a side elevation of the assembled apparatus. Fig. 2 is a top plan view thereof. Fig. 3 is an enlarged detail sectional view on the longitudinal medial line looking upwardly in Fig. 2. Fig. 4 is a similar enlarged detail sectional view looking in the reverse direction. Figs. 5 and 5a are transverse sectional views in the axial plane of the printing cylinder. Fig. 5a is an enlarged view showing the driving connection between the printing cylinder actuating means and the printing cylinder. Fig. 6 is a detail view of a chain belt paper feed device. Figs. 7 and 8 are top and side elevations of the paper feed chain. Fig. 9 is a detail view of a further modification of the paper feeding means. Figs. 10 and 11 are detail views of the auxiliary or signature printing roller. Figs. 12 and 13 are perspective views illustrating the successive operations performed upon the paper web, Fig. 12 illustrating the paper punched for pin wheel or chain feeding operation, while Fig. 13 illustrates the paper punched for use with the feeding device illustrated in Fig. 9. Fig. 14 illustrates a modified form of web material and feeding perforations. Figs. 15 and 16 are top plan and side elevations of the adjustable cut-off mechanism. Fig. 17 is a detail of a modified feeding device. Fig. 18 is a perspective view of an auxiliary paper supply mechanism for relieving the feeding and imprinting mechanism of the tension strain of drawing

the material from the supply roll. Fig. 19 is a detail view of the adjustable drive mechanism for such auxiliary feeding device. Figs. 20 and 21 are perspective views of the paper strips which have been partially cross cut during the initial imprinting operations preparatory to being passed through the present apparatus, whereby the severance of marginal strips containing feed holes will automatically effect division of the strip into successive sheets. Fig. 20 discloses a succession of closely spaced marginal holes while Fig. 21 shows more widely spaced marginal holes, one in each succeeding form. Fig. 22 is a perspective view of a supply packet of a zig-zag folded material which may be substituted for a supply roll.

Like parts are indicated by similar characters of reference throughout the several views.

The apparatus forming the subject matter hereof as illustrated in the drawings is mounted upon and between parallel side frames 1-1 mounted upon a base 2 and interconnected at spaced intervals by suitable tie bars.

The web of continuous series connected stationery is supplied from a roll 3 journaled on the frame 1 at one end of the apparatus from which the web passes over a guide roll 4, thence over a guide table 5 and between the printing cylinder 6 and a coacting platen 7 having operating contact through a suitable opening in the table.

Beyond the printing cylinder the web passes beneath a signature imprinting roll 8, which may, however, be employed for other printing impressions in differently colored ink or in locations upon the web outside the impression area of the printing cylinder 6. Continuing its course over the table 5, the marginally punched web is engaged by pin wheel feed devices 9 by which the web is positively advanced through successive movements proportionate to the length of the finished sheets, the extent of which is variable at will.

The impression contact of the printing area of the rotating cylinder 6 with the paper against the platen roll 7 would ordinarily be sufficient to insure unison travel of separate sheets of paper web when properly fed so long as the impression contact is maintained on a single form. It is desired, however, to advance a paper web drawn from a roll of continuous forms, a selected predetermined distance at each operation sufficiently to compensate for the portion of the sheet occupied by the letter head and a suitable space at the end and preceding the imprinted matter to afford, to the printed letter or form, a presentable balanced appearance and uniform length. This feeding motion of the paper web therefor varies in extent according with the size of the ultimate printed sheet, the extent of the letter head area and that used for "balancing" the imprint material on the sheet. Any slight differential or error of the feeding movement which would be quite unnoticeable on sheets singly fed would be accumulative on continuous web material and after a few impressions such differential would become quite serious.

In order to secure accurate registry upon succeeding sheets, it is therefore necessary that the advance of the material intermediate the impression periods be quite accurately effected. Hence the use of positive pin wheel feed devices 9 is preferred.

After having served its purpose of accurately and uniformly feeding the paper web, the punched

margins thereof are trimmed off by being passed under rotary cutters 10 and finally the printed web, minus its punched margins, is transversely divided at regularly spaced intervals by a "chopper" type of cutter 11.

Power is applied through the main drive shaft 12 (beneath the printing cylinder which carries a gear pinion 13 meshing with a corresponding pinion 14 upon the platen roll 7. The platen roll pinion meshes with a large gear wheel 15 fixedly connected to the printing cylinder 6 and rotating in unison therewith. The printing cylinder is thus given continuous rotary motion, always in the same direction. The printing cylinder gear 15 operating through a gear pinion 16 drives a gear 17 upon a transverse shaft 18 which, at the opposite side of the apparatus, carries a rotary cam 19. The cam 19 operating through a pitman 20 having a roller 21 traveling in the cam slot 22 oscillates to and fro a pivoted gear sector 23. The gear sector 23 intermeshes with a small gear pinion 24 loose upon the printing cylinder shaft 25 and connected through a friction clutch 26 with an oscillating disc 27 also loosely journaled upon the printing cylinder shaft 25 for free to and fro oscillation. The oscillatory disc 27 is peripherally grooved to receive relatively adjustable stops 28 of which there are two slidably adjustable in the peripheral groove and are adapted to be locked in their adjusted positions. The periphery of the disc is preferably, though not necessarily, serrated to receive and hold the stop lugs 28 which are similarly serrated for interlocking engagement. These stop lugs 28 contact with limiting stops 30 and 31 respectively, upon the frame of the apparatus at the limit of the oscillatory movement of the disc in either direction. The extent of such oscillatory motion is determined by the relative positions of the adjustable stop lugs 28. The engagement of such lugs with the fixed stops 30 and 31 limits the oscillation of the disc and any differential movement of the actuating gear sector 23 is compensated for by slippage of the friction clutch 26. Thus while the actuating gear sector describes a full stroke motion at each operation, the disc 27 moves in unison therewith through a portion only of such stroke until arrested by engagement of one or the other pair of stop lugs, whereupon the gear sector 23 continues its movement rotating the gear pinion 24 idly by slipping 50 the clutch 26.

The oscillatory disc carries a pawl 32 at its inner side, engaging with a ratchet wheel 33 also loosely journaled upon the printing cylinder shaft 25, with which is fixedly connected for unison rotation a large gear wheel 34 substantially equal in size to the printing cylinder gear 15 at the opposite side of the apparatus. Due to the interposed pawl and ratchet driving connection 32-33 the large gear wheel 34 is intermittently rotated in unison with the oscillation of the disc 27 and gear sector 23 in one direction but remains at rest in its advanced position during retrograde movement of such parts. The degree of motion transmitted to the gear wheel 34 at each actuating movement 65 is determined by the relative spacing of the limiting stops 28 upon the oscillatory disc. Thus the continuous motion of the driving mechanism is transformed into intermittent motion of the paper feed devices, the extent of which may be 70 varied to accommodate letters, bills or forms of different length.

The intermittently operated gear wheel 34 is operatively connected through a train of idler gears 35, 36, 37, 38, 39 and 40 with a gear wheel 41 75

upon a shaft 42 carrying the pin wheel feed devices 9 to which intermittent motion is thus transmitted. By this means the paper web is advanced uniformly with the rotation of the printing cylinder while the printing form is in contact therewith and is further advanced in unison with the rotation of the cylinder either before or after the engagement therewith of the printing form, but such unison movement is not continuous and the paper web comes to rest while the cylinder continues to rotate to present the type form in position for the succeeding printing impression upon the web.

The peripheral pins of the pin wheel feed devices 9 project through registering slots in the feed table 5 into feeding engagement with the marginal holes in the paper web. The feed table is preferably divided and the section contiguous to the pin wheels is pivotally mounted to afford access to such wheels. The web is maintained in feeding engagement with the pins by an overlying keeper plate 43 which is slotted at 44 for the passage of the feeding pins in their rotary travel. The keeper plate 43 is carried upon swinging arms 45 pivoted at 46, one of which is provided with a peripherally notched head 47 for engagement of a detent 48 by which the keeper plate is supported in slightly elevated relation above the feeding table 5 to minimize friction. The pivotal mounting of the keeper plate enables it to be turned to an inoperative position to facilitate insertion and initial adjustment of the paper web upon the pin wheels 9.

Located beyond the feeding wheels 9 are parallel spaced trimming discs 10 cooperating with a platen roller 50 between which the paper web advances, and by which the punched margins of the web are simultaneously trimmed off. The cutters or trimming discs 10 are adjustably mounted on swinging arms 51 and adjusted relative to the platen roll by the adjusting screw 52. Idler rollers 49 are mounted adjacent to the trimming discs 10 and hold the paper web on the platen 50.

Finally the advancing paper web is engaged by a transverse cutter by which it is divided at spaced intervals into succeeding separate sheets, each of which bears the imprint of the type or marking devices carried by the printing cylinder in accurately predetermined position upon the sheet which may also bear a previously printed letter head or other data or indicia.

The transverse cutter may be of various forms, a quite simple construction consists of a stationary cutter bar 53 mounted upon the main frame with which cooperates a sweep 54 carrying a coacting transverse cutter bar 11. Such sweep arms are adjustably carried upon the revoluble shaft 56 upon which is mounted a driven gear 57 to which motion is transmitted by idler gears 58 and 49 forming a continuation of the gear train operating the pin wheel feed devices. Being operated through the same driving train the cutter functions in timed relation with the web feeding devices. Sheets of different length are accommodated by adjusting the sweep arms to different radial positions about the shaft thereby changing the timed relation of the cutter knife.

The preferred form of cutter comprises a head 60 slidably mounted upon guide rods 61 supported in a cross bar 62 of the main frame and projecting longitudinally therebeyond. The guide rods are preferably provided with rack teeth 63 for engagement of pinions carried by the head 60 and rotatable by the crank 64 to slidably ad-

just the cutter head. Mounted in the cutter head 60 is a vertically sliding knife bar 65 carrying a cutter blade 66, the cutting edge of which is upturned for cooperation with a second knife 67 stationarily carried upon the head 60. The paper web is progressively advanced between such knives. The sliding knife bar 65 is normally held retracted by a spring 68 and is guided between the rear side of the head 60 and an adjustable bearing or guide plate 69 mounted upon the head. The movable knife 66 has an upwardly projecting guide or lead finger 70 overlapping the end of the stationary knife 67 to insure proper sliding relation therebetween.

The sliding knife 66 is actuated against the tension of its retracting spring by a pivoted lever plate 71 engaging with a stud 72 on the knife bar 65 and in turn oscillated by a bell crank lever 73. The bell crank lever is connected by a link 74 with a rock arm 75 slidably adjustable on a rock shaft 76 extending longitudinally of the machine. At its opposite end the rock shaft carries a similar rock arm 77 connected by a similar link with a small cam arm 78 which is engaged by a roller stud upon the cam 19' at each rotation of the cam which actuates the gear sector 23, thereby transmitting to the shaft 76 intermittent rocking motion. The shaft and rock arm 75 are splined for relative adjustment longitudinally of the shaft in unison with the adjustment of the cutter head 60, as may be necessary to accommodate sheets of different sizes. The links 74 are provided with double pivotal or universal joints to enable them to compensate for rocking motion of the respective connected arms in different planes.

While the pin wheel feed devices 9, before described, are preferred for intermittently advancing the paper web, in lieu thereof enlarged pin wheels 19 may be mounted concentrically with the printing cylinder upon the cylinder shaft 25 and connected with the intermittently operated gear wheel 34 for unison rotation. In such case one such enlarged pin wheel is provided at each side of the printing cylinder. These pin wheels 19 are interconnected for unison rotation with the intermittently actuated large gear 34. If such enlarged pin wheel feed devices are employed, the smaller pin wheels 9, before described, are omitted and vice versa.

As a further modification chain belts 80 shown in Figs. 6, 7 and 8 may be substituted for the pin wheels 9. In such case the traveling chain belt may be located at the present position of the pin wheels 9, but is preferably located immediately beneath the printing cylinder. In such position it is actuated by sprockets 81 upon the platen roll shaft 14 immediately beneath the cylinder. The studded feeding chain is guided over idler sprockets 82 located in spaced relation on opposite sides of the actuating sprocket 81. The feeding table is slotted at 80' to accommodate the feeding chains 80, the studs of which engage marginal holes punched in the paper web. By use of the chain the marginal feeding holes 65 may be located at greater distances apart.

In Fig. 9 there is shown a friction feed mechanism comprising a series of relatively adjustable overlapping sectors 109 which cooperate with a friction roll 110 to advance the paper web, the extent of advance being determined by the adjustment of the sectors. By relatively adjusting the sectors and securing them in such adjusted positions, the periphery of the feeding device may be extended or contracted. The paper is

advanced by being frictionally engaged between the periphery of the sectors of the feeding device and the coacting friction roll. A single stud or feeding pin 111 carried by one of the sectors operatively engages in spaced feeding holes in the paper to insure the initiation of advance movement in proper time with the printing devices. This feeding means is shown and described in patent to Sherman No. 1,529,555, and, per se, forms no part of the present invention except in combination with associated parts.

In printing form letters it is quite desirable to imprint a facsimile signature in differently colored ink, or it is sometimes desirable for emphasis to print "fill ins" of different color. For this purpose there is provided an auxiliary printing mechanism.

The continuously rotating cylinder gear 15 intermeshes with an idler pinion 84 transmitting motion to a gear 85 upon a transverse shaft 86, upon which is mounted for rocking motion an eccentric sleeve 87. Journaled upon the eccentric sleeve 87 is the auxiliary printing roller 8 bearing impression plates or type as may be required. The printing roller is operatively connected with the drive shaft 86 for unison rotation by compensating coupling heads 89-90. The head 89 is fast upon the shaft 86 and has in its lateral face diametrically opposite radial slots 89' within which engage splines or lugs on the floating collar 90 which also is provided with similar diametrically opposite radial slots 90' disposed in right angle relation with the slots 89' of the fixed collar 89. The radial slots of the floating collar are engaged by splines or lugs upon the end of the printing roller 8 to rotate such roller about the stationary eccentric sleeve 87. The eccentricity of the driving and driven rotating members is compensated for by a lateral shifting adjustment of the floating collar 90 relative to the fixed collar 89 and the roll 8 with both of which it is slidingly engaged for transverse motion, the motion relative to the respective members being at right angles.

The eccentric sleeve 87 is normally so positioned that the roller rotates in an elevated idle position above the level of the paper. By rocking the eccentric sleeve 87 about the drive shaft 86, the roller is lowered into impression contact with the paper web without, however, interfering with its rotation. To rock the eccentric sleeve in proper timed relation there is provided on the end of the shaft 86 opposite the driving gear 85, a small gear pinion 91 intermeshing with a gear wheel 92 having therein a cam groove 93 within which engages a roller upon an oscillatory lever 94 operable against the tension of a retracting spring 94'. The cam is so shaped that the lever is held stationary first in one position and then in another position while the gear and cam continue to rotate. The cam is so shaped that the lever is held in one position through a much greater time interval than in its other position. The lever 94 is connected by a link 95 with a rock arm 96 upon the eccentric sleeve 86. As the lever 94 is oscillated from its normal position to its operated position in which it is temporarily held by the cam, it actuates the rock arm 96 thereby turning the eccentric sleeve to lower the printing roller into impression making contact with the paper web.

The gear train is so proportioned that the printing roller may make several rotations in its inoperative position before being lowered into impression making contact by actuation of the lever

94 and makes but one rotation therein before being returned. The printing roller is supplied with ink from a roller pad 97 by a transfer roller 98 driven through the gear pinions 99-100 and 101 from the auxiliary printing roller shaft 86.

The printing cylinder is preferably, though not necessarily, of the type commonly employed for multigraphing purposes. It consists of spaced heads 102 and 103 upon which is removably mounted a semi-circular slotted type chase 104 within the slots of which the printing type are assembled. The chase is held upon the heads by a hook 105 having locking engagement with the cylinder shaft 25. The respective heads 102 and 103 carry mounting means 106 and automatic feeding mechanism 107 for supply and receiving rollers 108 upon which is carried an ink ribbon or apron 112 extending around the periphery of the cylinder and over the type body or printing plate. The impression is effected through such inked apron in the manner well known in duplicating apparatus. It is obvious, however, that the type may be inked by an ink transfer roll receiving its supply from a roller pad or from an ink fountain as is customary in printing apparatus and as shown in association with the auxiliary or signature printing roller. The particular detail construction of the type chase and ink ribbon or apron feeding mechanism forms no part, per se, of the present invention.

In lieu of marginally punched paper as before described, the paper web may be medially punched at spaced intervals for engagement of feeding devices as shown at 113 in Fig. 14 in which case instead of trimming off punched marginal strips, the cutter is provided with double spaced blades which sever the web on spaced transverse lines 114 at opposite sides of the feeding holes 113, thus removing a transverse punched strip between succeeding imprinted sheets. In such construction one cutter blade severs the imprinted sheet from the web and the second blade trims the intermediate punched feeding portion from the advance end of the web.

The use of the present apparatus enables the rapid, accurate and economical production of multi-form letters, circulars and other printing operations. By employing stationery preprinted in roll form a great saving in material and printing costs is effected. The present apparatus accurately positions its impressions with the prior imprints upon the roll material, and the positive paper feeding means automatically and continuously maintains such relation. The work can be performed more rapidly and less expensively than is possible with the usual more expensive duplicating machines requiring feeders for flat forms.

While the printing of successive impressions upon continuous web material is quite common, ordinarily a slight variation in the spacing of successive impressions is quite immaterial. The present material being preprinted with letter headings, forms or other indicia, in definite relation with which additional imprints are to be made by the present apparatus, any variation however slight in the feeding of the web relative to the printing apparatus results in defective production. Hence positive feeding devices are employed to insure accurate registry which would otherwise be unnecessary if printing upon blank webs. Likewise the letterheads, forms or other matter, preprinted upon the web, must be accurately spaced.

In order that the synchronized feeding and imprinting mechanism may be relieved of tension

and pulling strain incident to withdrawing the material from a heavy supply roll 3, an auxiliary pin type roller 115 may be provided above the supply roll 3, the pins 116 of which have progressive engagement with the marginally punched holes in the strip of material. This pin type roller is actuated from the drive gear 17 by a variable frictional drive mechanism.

As shown in Figs. 18 and 19 there is journaled in brackets 117 up on the side frame 1 of the apparatus a revoluble shaft 118 having at its upper end a bevel gear pinion meshing with a corresponding gear pinion on the shaft of the roller 115. A friction wheel 119 having driving engagement with the shaft 118 project through an opening in the side frame 1 into engagement with the driving gear 17. The friction wheel and its mounting are adjustable longitudinally of the shaft and radially toward and from the center of the gear 17 by an adjusting screw 120. To enable adjustment of the friction wheel toward the gear 17 to compensate for wear and maintain requisite driving pressure, the wheel 119 is loosely journaled upon an eccentric bushing surrounding the shaft. The bushing is revolvably adjustable thereon by means of an adjusting lever 121 operative in an arcuate slot 122 of a segment plate 123 carried by the wheel mounting. A nut 124 serves to hold the bushing in its adjusted position. The friction wheel thus rotates about an axis somewhat eccentric with that of the shaft 118. Secured to the shaft immediately beneath the wheel for unison rotation is a disc like collar 125 having therein a radial slot 126 into which projects a driving stud carried by the wheel. Thus the disc 125 and shaft 118 are rotated in unison with the eccentrically positioned friction wheel.

While the strip feeding mechanism synchronized with the imprinting means is intermittently actuated, the auxiliary feeding roller 115 is continuously driven to draw from the roll a supply of material which droops in a loose bight or loop 127 intermediate the auxiliary feeding roller and the imprinting devices and associated synchronized feeding means. The speed of the auxiliary roller is timed, by adjustment of the friction wheel, to maintain ample slack or excess material in the loop 127, from which the material passes to the imprinting and feeding apparatus.

While as before described, the material may be transversely severed into succeeding sheets by a cutter operating in synchronism with the imprinting and feeding apparatus, such cutter may be omitted and the strip of material may be partially severed at spaced intervals before being fed to the present apparatus. In Figs. 20 and 21 the strip material is shown as comprising a succession of sheets interconnected only contiguous to their side margins. Between each succeeding form of sheet is a transverse cut 128 which terminates in spaced relation with the side edges. After the strip has passed through the machine its engagement with the trimmers will detach such marginal strips on lines intersecting the cross cuts substantially coincident with the ends thereof thus freeing succeeding forms or sheets from each other. Although a continuous succession of spaced holes are preferably provided in the margins of the strip material as shown in Fig. 20, a lesser number of more widely spaced feed holes may be provided as shown in Fig. 21. Whether cross cut between succeeding forms as shown in Figs. 20 and 21 or continuous as shown in Figs. 12, 13 and 18, the material may be reversely folded into packet form preferably at

spaced intervals, coincident with the lines upon which the material is to be subsequently severed, as shown in Fig. 22.

The present arrangement of parts and control of the feeding and imprinting means enables the use of printing plates of different length, and hence engageable through greater or less portions of the cycle the positive feeding means is adjustable for different lengths of forms and does not operate continuously at the same rate of speed as the printing cylinder. Obviously, during such period as the printing cylinder is in contact with the web to which it imparts a simultaneous frictional feeding impulse, the feeding means must be synchronized therewith, but during the intervening intervals the feeding device may be differentially operated either at a reduced or increased speed, or it may be operative during a portion of the intervening interval between succeeding impressions and at rest during the remainder of the intervals. The necessary extent of feeding movement is that portion of the form upon which the imprinting device operates plus sufficient additional movement necessary to advance the web during non-printing intervals to present the succeeding impression receiving area in position for engagement of the imprinting device.

Cross reference is made to copending companion applications Serial No. 116,552, filed December 18, 1936, Serial No. 226,670, filed August 25, 1938, and Serial No. 279,341, filed June 15, 1939.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect and the invention is therefore claimed in any of its forms or modifications within the legitimate and valid scope of the appended claims.

Having thus described my invention, I claim:

1. A strip feeding and imprinting apparatus wherein a length of impression receiving material having therein marginally disposed longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by an impression making apparatus for impressing the web of material while being fed by said traveling pin feed devices, trimming means for removing the marginal portions from the web containing the longitudinally spaced holes in seriatim with the impression apparatus, and a transverse cutter dividing the printed and trimmed web into successive sheets.

2. A strip feeding and imprinting apparatus wherein a length of impression receiving material having therein marginally disposed longitudinally

- spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by a trimmer for removing portions of the web engaged by the feeding means, and a cutter for severing succeeding printed portions from the web.
3. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by actuating means for transmitting to the impression apparatus continuous operation and for transmitting to the web feeding means intermittent operation, and means for varying the extent of the positive web feeding operation independently of the operation of the impression apparatus.
- 30 4. A strip feeding and imprinting apparatus wherein a length of impression receiving material having therein marginally disposed longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by trimming means for longitudinally slitting the web to remove the margins at a point within the line of longitudinally spaced holes after passing the feeding means, and a cutter for transversely severing successive lengths of printed and trimmed material from the web.
5. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by a rotary printing cylinder, and differential actuating means for operating the web feeding means in unison with the rotation of the cylinder throughout a portion of its rotation and arresting the web feeding means during the remainder of the rotation of the cylinder, and a cutter for severing successive lengths of printed material from the web.
- 65 6. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by a rotary printing de-
- vice for impressing the web at spaced intervals, and differential driving means for the feeding means for advancing the web in unison with the printing device during a portion of the travel movement thereof and thereafter arresting the advance of the web during the remainder of the travel movement of the printing device, and a cutter for severing successive lengths of printed material from the web.
7. A strip feeding and imprinting apparatus wherein a length of impression receiving material having therein marginally disposed longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by an impression making device, repetitiously engaging the traveling web, means for actuating the web feeding means differentially with the impression making device, and a cutting device for cutting printed lengths of predetermined extent from said web.
8. The herein described method of producing duplicate printed forms from a length of impression receiving material having therein marginally disposed longitudinally spaced holes, consisting in progressively feeding a web of impression receiving material past an impression making apparatus by a pin type feeding device including an endless traveling series of strip engaging pins progressively engageable in succeeding longitudinally spaced holes in the strip, longitudinally slitting the web to remove its marginal edges containing the longitudinally spaced holes, and transversely dividing the printed and trimmed web into a succession of printed sheets.
- 30 9. The herein described method of producing duplicate printed forms from a length of impression receiving material having therein marginally disposed longitudinally spaced holes, consisting in progressively feeding the strip past an impression making apparatus by a pin type feeding device including an endless traveling series of strip engaging pins progressively engageable in succeeding longitudinally spaced holes in the strip, longitudinally slitting the web of material to remove the margins and the longitudinally spaced holes therein and subsequently transversely cutting the printed and trimmed web into a succession of sheets.
- 35 10. A strip feeding and imprinting apparatus wherein a length of impression receiving material having therein marginally disposed longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by a trimming means for removing from the web the portion having therein longitudinally spaced holes engaged by the feeding apparatus.
- 40 11. A strip feeding and imprinting apparatus wherein a length of impression receiving material having therein longitudinally spaced feed holes is periodically advanced through a step by step movement past an imprinting position of such apparatus to receive imprinted legends

thereon at predetermined spaced intervals by a pin type feeding device including an endless traveling series of strip engaging pins progressively engageable in succeeding longitudinally spaced holes in the strip, characterized by means for actuating the impression making apparatus and the web feeding device differentially for presenting the web material in predetermined registering relation with the printing apparatus at each operation thereof.

12. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by means for actuating feeding device to register predetermined portions of the web with the impression making apparatus.

13. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by actuating means for intermittently operating the web feeding device through steps of variable extent, and means for varying the feeding movement of said device.

14. A strip feeding and imprinting apparatus wherein a succession of printed forms connected end to end in continuous succession and having therein longitudinally spaced feed holes are to be additionally imprinted in predetermined relation with the previously printed matter and are periodically advanced through a step by step movement past an imprinting position of such apparatus to receive imprinted legends thereon at predetermined spaced intervals by a pin type feeding device, including an endless traveling series of strip engaging pins progressively engageable in succeeding longitudinally spaced holes in the forms, characterized by actuating means for differentially actuating the imprinting and feeding devices to insure registry of the previously printed forms in predetermined relation with the imprinting device.

15. A strip feeding and imprinting apparatus wherein a succession of printed forms connected end to end in continuous succession and having therein longitudinally spaced feed holes are to be additionally imprinted in predetermined relation with the previously printed matter and are periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the forms, characterized by actuating means for intermittently operating the feeding device for presenting the preprinted forms successively in position to receive further imprint from said imprinting device.

75 16. A strip feeding and imprinting apparatus

wherein a succession of printed forms connected end to end in continuous succession and having therein longitudinally spaced feed holes are to be additionally imprinted in predetermined relation with the previously printed matter and are periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the forms, characterized by actuating means common to the imprinting and feeding devices, said means operating the imprinting device through a continuous cycle and operating the feeding device intermittently in unison with the imprinting device.

17. A strip feeding and imprinting apparatus wherein a succession of printed forms connected end to end in continuous succession and having therein longitudinally spaced feed holes are to be additionally imprinted in predetermined relation with the previously printed matter and are periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the forms, characterized by means for varying the extent of operation of the feeding device independently of the extent of operation of the imprinting device.

18. A strip feeding and imprinting apparatus wherein a succession of printed forms connected end to end in continuous succession and having therein longitudinally spaced feed holes are to be additionally imprinted in predetermined relation with the previously printed matter and are periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the forms, characterized by a trimmer for removing from the series connected forms the portions thereof engaged by the feeding device, and a cutter for severing succeeding imprinted forms from the interconnected succession.

19. In an apparatus wherein a succession of printed forms connected end to end in continuous series are to be imprinted in predetermined relation with the previously printed matter, an imprinting device, a feeding device engaging the series connected printed forms for advancing same past an impression receiving position, said interconnected forms having holes therein for engagement of the feeding device and cutting and trimming means for severing the connected imprinted forms one from another, and for removing therefrom the portions having feeding holes therein in seriatim with operation of the imprinting device.

20. A strip feeding and imprinting apparatus wherein a succession of printed forms connected end to end in continuous succession and having therein longitudinally spaced feed holes are to be additionally imprinted in predetermined relation with the previously printed matter and are periodically advanced through a step by step movement past an imprinting position of

such apparatus to receive imprinted legends thereon at predetermined spaced intervals by a pin type feeding device including an endless traveling series of strip engaging pins progressively engageable in succeeding longitudinally spaced holes in the forms, characterized by actuating means transmitting to the imprinting device a continuous motion into and out of imprinting engagement with the succeeding printed forms, and actuating means intermittently advancing the interconnected forms predetermined distances intermediate succeeding imprinting engagements to accurately register the succeeding forms with the imprinting device, and means for varying the extent of such movement intermediate printing operations.

21. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by a driving means for the feeding means, and printing device for advancing the web in unison with the printing device during a portion of the travel movement thereof and thereafter arresting the advance of the web during the remainder of the travel movement of the printing device.

22. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by a rotary imprinting cylinder engageable with the travelling web during only a portion of its rotation, means for actuating the aligning and feeding means and the imprinting cylinder in unison during a part of the cycle of operation while the web and cylinder are in imprinting engagement with each other, and thereafter for a portion only of the remainder of the rotation of the cylinder.

23. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by a rotary imprinting cylinder engageable with the travelling web during only a portion of its rotation, means for actuating the aligning and feeding means and the imprinting cylinder in unison during a part of the cycle of operation while the web and cylinder are in imprinting engagement with each other and for actuating the aligning and feeding means differentially with the imprinting cylinder during the remainder of the rotation thereof.

24. A strip feeding and imprinting apparatus

wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by an actuating means for the strip feeding device by which the strip is advanced during only a portion of the interval between succeeding engagements of the imprinting device therewith.

25. A strip feeding and imprinting apparatus wherein a length of impression receiving material having therein longitudinally spaced feed holes is periodically advanced through a step by step movement past an imprinting position of such apparatus to receive imprinted legends thereon at predetermined spaced intervals by a pin type feeding device including an endless traveling series of strip engaging pins progressively engageable in succeeding longitudinally spaced holes in the strip, characterized by and control means for the strip feeding device by which the advancement of the strip is arrested during a portion of the interval between succeeding engagements of the imprinting device therewith.

26. A strip feeding and imprinting apparatus wherein a length of impression receiving material having therein longitudinally spaced feed holes is periodically advanced through a step by step movement past an imprinting position of such apparatus to receive imprinted legends therein at predetermined intervals by a pin type feeding device including an endless traveling series of strip engaging pins progressively engageable in succeeding longitudinally spaced holes in the strip, characterized by means for actuating the feeding device to advance the strip past an impression receiving position in synchronism with the imprinting operation during the engagement of the imprinting device therewith and for further non-synchronously advancing the strip during intervals of non-engagement of the imprinting device.

27. An imprinting apparatus wherein a continuous strip of material receives successive impressions at spaced intervals, an imprinting device, an intermittently operative strip feeding device for advancing the paper relative to the imprinting device past an impression receiving position, the advancement thereof being momentarily arrested between succeeding movements thereof, and a second continuously operative feeding device for drawing the strip material from a source of supply and advancing it to the first mentioned feeding device while maintaining a loop of slack material between said feeding devices, and means for actuating the respective feeding devices, one intermittently and the other continuously in synchronism with the imprinting device.

28. In a strip feeding apparatus, the combination with an imprinting mechanism of dual strip feeding means including an intermittently operated pin type feeding device having engagement in succeeding spaced holes in the strip for advancing the material through a step by step motion past the imprinting position and a second continuously operative pin type feeding device also having engagement in succeeding spaced holes in the strip for drawing the strip material from a source of supply and advancing the with-

drawn material to the first mentioned feeding means while maintaining a loop of slack material therebetween, common actuating means for the feeding devices and means for adjustably varying the rate of feed of one feeding device relative to the other.

29. In a strip feeding and imprinting apparatus wherein a continuous strip of record material having therein a marginal succession of longitudinally spaced feed holes is progressively advanced by a pin type feeding device past an imprinting position at which prescribed longitudinally spaced areas thereof receive imprinted legends and wherein the marginal punched area is removed subsequently to feeding engagement of the pin type feeding device with the longitudinally spaced holes and the remainder of the strip severed intermediate the imprinted areas into individual imprinted sheets, the combination with an imprinting device, a strip trimming device for removing punched margins thereof, and a strip severing device, of a pin type feeding device common to the imprinting, trimming and severing devices, and so constructed and arranged as to feed the strip in timed relation with the several devices to present prescribed longitudinally spaced areas thereof in registry with the imprinting position coincident with the operation of the imprinting device and to present other longitudinally spaced predetermined areas thereof in accurate registry with the strip severing device coincident with the operation thereof and for advancing the strip past the trimming device.

30. In a strip feeding and imprinting apparatus wherein a continuous strip of record material having therein a marginal succession of longitudinally spaced feed holes is progressively advanced by a pin type feeding device past an imprinting position at which prescribed longitudinally spaced areas thereof receive imprinted legends and wherein the marginal punched area is removed subsequently to feeding engagement of the pin type feeding device with the longitudinally spaced holes and the remainder of the strip severed intermediate the imprinted areas into individual imprinted sheets, a strip imprinting device, and a traveling pin type feeding device for progressively advancing the strip past printing position and successively registering prescribed longitudinally spaced areas therewith coincident with the operation of the imprinting device to imprint thereon a succession of legends at predetermined spaced intervals.

31. In a strip feeding and imprinting apparatus wherein a continuous strip of record material having therein a marginal succession of longitudinally spaced feed holes is progressively advanced by a pin type feeding device past an imprinting position at which prescribed longitudinally spaced areas thereof receive imprinted legends and wherein the marginal punched area is removed subsequently to feeding engagement of the pin type feeding device with the longitudinally spaced holes and the remainder of the strip severed intermediate the imprinted areas into individual imprinted sheets, a strip severing device for transversely dividing the strip at longitudinally spaced intervals into a succession of individual sheets, and a traveling pin type feeding device engageable in the longitudinally spaced holes of the strip for advancing the strip in timed relation with the operation of the severing device for accurately presenting succeeding predetermined longitudinally disposed areas thereof in registry with the severing device.

32. In a strip feeding and imprinting apparatus wherein a continuous strip of record material having therein a marginal succession of longitudinally spaced feed holes is progressively advanced by a pin type feeding device past an imprinting position at which prescribed longitudinally spaced areas thereof receive imprinted legends and wherein the marginal punched area is removed subsequently to feeding engagement of the pin type feeding device with the longitudinally spaced holes and the remainder of the strip severed intermediate the imprinted areas into individual imprinted sheets, a strip trimming device, and a pin type feeding device engageable in the marginal holes of the strip for advancing the strip relative to the trimmer device in synchronism with the imprinting and severing of the strip at predetermined spaced intervals.

33. A strip feeding and imprinting apparatus wherein a continuous strip of record material having therein a marginal succession of longitudinally spaced feed holes is progressively advanced by a pin type feeding device past an imprinting position at which successive prescribed areas of the strip are imprinted and wherein the punched marginal area of the strip is removed subsequently to feeding engagement of the pin type feeding device with the longitudinally spaced holes and the strip transversely divided into a succession of individual sheets, characterized by an imprinting device, a marginal trimming device, a strip severing device, and a pin type feeding device associated therewith for progressively advancing the strip relative to the trimming device in synchronized relation with the imprinting and strip severing devices whereby predetermined longitudinally spaced areas will be accurately registered with the imprinting device to receive imprinted impressions thereon and prescribed longitudinally spaced division lines will be accurately registered with the strip severing device for division of successive portions from the main strip.

34. A strip feeding and imprinting apparatus wherein a continuous strip of record material having therein a marginal succession of longitudinally spaced feed holes is progressively advanced by a pin type feeding device past an imprinting position at which successive prescribed areas of the strip are imprinted by engagement of a traveling pin type feeding device in said feed holes and wherein the marginally punched area is removed subsequently to feeding engagement of the pin type feeding device with the longitudinally spaced holes, characterized by a strip severing device for transversely dividing the strip into a succession of individual sheets at predetermined spaced intervals, said pin type feeding device being duofunctionally effective to progressively present predetermined transverse longitudinally spaced division lines in accurate registry with the strip severing device coincident with the operation thereof in addition to its function of registering prescribed areas of the strip with the imprinting position coincident with the operation of an imprinting device.

35. A strip feeding and imprinting apparatus wherein a continuous strip of record material having therein a marginal succession of longitudinally spaced feed holes is progressively advanced past an imprinting position at which successive prescribed areas of the strip are imprinted by engagement of a traveling pin type feeding device in said feed holes, and the strip subsequently transversely divided intermediate succeeding im-

- printed impressions into individual sheets, characterized by trimming means for removing the marginally punched area of the strip therefrom prior to its transverse division into individual sheets, said pin type feeding device being duofunctionally effective to advance the strip relative to the trimming device and simultaneously present predetermined longitudinally spaced areas thereof in registry with severing and imprinting 10 positions of the apparatus.
36. A strip feeding and imprinting apparatus wherein a strip of impression receiving material having therein longitudinally spaced feed holes is progressively advanced past an imprinting position of such apparatus to receive imprinted legends thereon at predetermined spaced intervals, characterized by a pin type feeding device including an endless traveling series of strip engaging pins progressively engageable in succeeding longitudinally spaced feed holes in the strip for advancing the strip, an impression making apparatus for impressing the strip of material while the strip is being fed by said pin type feeding device, trimming means for removing the portions 25 of the strip containing the longitudinally spaced feed holes in seriatim with the operation of the impression making apparatus, and a device for transversely dividing the printed and trimmed strip into successive sheets.
37. A strip feeding and imprinting apparatus wherein a strip of impression receiving material having therein longitudinally spaced feed holes is progressively advanced by a pin type feeding device past an imprinting position at which successive prescribed areas of the strip receive imprinted legends, and wherein portions of the strip containing the longitudinally spaced feed holes are removed subsequently to feeding engagement of the pin type feeding device with the longitudinally spaced holes, characterized by a pin type feeding device including an endless traveling series of strip engaging pins progressively engageable in succeeding longitudinally spaced feed holes in the strip for advancing the strip, an impression making apparatus for imprinting the strip of material while the strip is being fed by said pin type feeding device, a trimming device for removing the portions of the strip containing the longitudinally spaced feed holes, said pin type feeding device being duofunctionally effective to progressively register prescribed areas of the strip with the imprinting position coincident with the operation of the impression making apparatus in addition to its function of advancing the strip 40 past the trimming device for removing the portions of the strip containing the longitudinally spaced feed holes.
38. A strip feeding and imprinting apparatus wherein a strip of impression receiving material having therein longitudinally spaced feed holes is progressively advanced past an imprinting position at which successive prescribed areas of the strip receive imprinted legends, characterized by a pin type feeding device including an endless traveling series of strip engaging pins progressively engageable in succeeding longitudinally spaced feed holes in the strip for advancing the strip, an impression making apparatus for imprinting the strip of material while the strip is being fed by said pin type feeding device, a device for transversely dividing the printed strip into successive individual imprinted sheets at predetermined spaced intervals, said pin type feeding device being duofunctionally effective to progressively present predetermined longitudinally spaced division areas in accurate registry with the strip dividing device coincident with the operation thereof in addition to its function of registering prescribed areas of the strip with the imprinting position coincident with the operation of the impression making apparatus, and its function of advancing the strip past the trimming device for removing the portions of the strip containing the longitudinally spaced feed holes. 45

CERTIFICATE OF CORRECTION.

Patent No. 2,177,675.

October 31, 1939.

JOHN Q. SHERMAN.

It is hereby certified that error appears in the printed specification of the above numbered patent requiring correction as follows: Page 2, second column, line 7, after the word "cylinder" insert a parenthesis; page 3, second column, line 19, for "cell" read bell; page 8, first column, line 27, claim 21, before "driving" insert differential; and second column, line 10, claim 24, before "actuating" insert intermittent; line 25, claim 25, strike out "and"; line 36, claim 26, for "therein" read thereon; line 37, same claim, for "including" read including; and that the said Letters Patent should be read with this correction therein that the same may conform to the record of the case in the Patent Office.

Signed and sealed this 19th day of December, A. D. 1939.
